UNITED STATES PATENT OFFICE

EUGENE J. MOYNIHAN, OF SAN FRANCISCO, CALIFORNIA.

ROCK-CARRYING STEAM-SHOVEL DIPPER.

1,263,790.

Specification of Letters Patent. Patented Apr. 23, 1918.

Application filed April 12, 1917. Serial No. 161,641.

To all whom it may concern:

Be it known that I, EUGENE J. MOYNIHAN, a citizen of the United States, residing at San Francisco, in the county of San Francisco and State of California, have invented new and useful Improvements in Rock-Carrying Steam-Shovel Dippers, of which the following is a specification.

The present invention relates to improvements in the dipper of steam shovels, dredgers or the like.

The object of the invention is to provide a dipper which, without any material increase in size, will unload a rock which is so large that it cannot be unloaded by the ordinary dipper unless it can be rolled. A further object is to provide such a dipper which, can be readily converted into a dipper of ordinary form when required.

In the accompanying drawing, Figure 1 as an end view of the operative portion of a steam shovel equipped with my improved dipper; Fig. 2 is an enlarged side view of the dipper; Fig. 3 is a bottom plan view thereof; Fig. 4 is a detail front view of the dipper detached, showing a large rock in position to be transported thereby.

Referring to the drawing, 1 indicates a frame, 2 a front truck, and 3 a dipper, of a steam shovel to which my invention is shown as applied. None of the parts thereof are new except the dipper itself, but I have illustrated the shovel in order the better to disclose the mode of use and advantages of my improved dipper.

The front portion 4 of the dipper is made of the usual form in its upper part having the usual cutting teeth, which, however form no part of the present invention, and it is formed integral with side pieces 5 which are secured on the outer sides of a yoke-shaped piece 6, from which extend rearwardly eyes 7, through which extends a pintle 8, said pintle also extending through eyes 9 formed on a plate 10 secured to the under side of the dipper handle 11 at its outer end.

From the central portion of the piece 6 extends upwardly a casting 54, in the form of an eye or bearing for a pivot pin by which is pivoted the usual bail 53.

To the outer sides of said side pieces 5 are secured, by rivets 12, cheek plates 13, the rear portions of which extend inwardly behind the back or central portion of the yoke-shaped pieces 6, as far as the eyes 7 and then rearwardly and upwardly in parallel planes,

as shown at 14, their upper ends being connected with the upper and front ends of back braces 15, the rear and lower ends of which are connected to a bolt 16 extending 60 transversely through the usual casting 17 secured on the top of the dipper handle 11.

The front 4 of the dipper is extended downward to about the same depth as the front of the ordinary dipper, but the dipper 65 handle is connected much nearer to the top than in the old construction, since it is pivotally secured to the lower portion of the back of the dipper, which is much shorter than that of the ordinary dipper. 70

A support 18 is attached to front ends of arms 19 which extend in large curves and are pivoted as shown at 20 at their rear ends to the upward extensions of the cheek plates 13, in the same manner as the arms of the 75 door of the dipper of the old form, but it is not now a door in the proper sense of the word, since it does not close the opening in the bottom of the dipper, but serves to support a large rock between itself and the dipper proper. A narrow strip 51 is removably attached to the arms 19 at the rear of the support 18 and forms a support section which is removed when it is desired to enlarge the opening between the dipper body 85 and the arms 19.

The arms 19 are provided with racks 22 which are engaged by pawls 23 on a shaft 24 extending in bearings at the under side of the dipper handle. To the bottom of the 90 supporter 18 are secured bearings 25 for a latch 26 which can enter a hole 27 in a metal plate 35 which extends on the front and rear sides of the lower end of the front of the dipper. This plate 35 not only supports 95 the front edge of the supporter, or of the door, in the modification hereinafter described, but reduces the wear on the front of the dipper, being changed as often as necessary. 100

To the rear end of the latch is connected one end of a chain 28 the other end of which is connected with a lever 29 pivoted on the under side of the dipper handle and the outer end of which is connected to a chain 105 30 leading to a point suitable for operation for withdrawing said latch from engagement with the front of the dipper. To said lever is attached one end of a chain 31, the other end of which is attached to one of 110 said pawls 23.

The supporter 18 is withdrawn by the

cable 32, the use of which is more particularly described in United States Letters Patent No. 1,210,194, Dec. 26, 1916.

The mode of use of this invention will be readily seen in reference to Figs. 1 and 4. It will further be seen that to raise and transport a large rock, shown at 33, the dipper is moved backward by the dipper handle so as to cause the lower portion of the front of the dipper to engage the lower surface of the rock and the side of the rock is engaged by the side walls of the dipper, and then the supporter is allowed to swing on its hinges until it engages the side of the rock opposite to that engaged by the dipper, and is retained in that position by means of the pawls engaging the racks. The rock is now raised and transported, to the place desired, as, for instance, to the top of a flat-car, and then the rock is first deposited upon the surface of the car, so as to withdraw the greater portion of its weight from the supporter, and then the pawls are withdrawn from the racks by the regular trip line and the supporter allowed to swing open and the whole of the rock is deposited upon the car, free from the dipper.

I claim:—

1. A dipper comprising sides, a back, a front having a downward extension below said sides and back, and a supporter hinged to the dipper and adapted to engage said extension at a point sufficiently below the dipper to leave an opening therebetween to carry a rock too large to be contained in the dipper, and means located on the side of said supporter remote from the dipper for preventing the supporter swinging away from the dipper.
2. A dipper comprising sides, a back, a front having a downward extension below said sides and back, a supporter hinged to the dipper and adapted to engage said ex-

tension at a point sufficiently below the dipper to leave an opening therebetween to carry a rock too large to be contained in the dipper, and a removable support section at the back of said support and carried therewith.

3. In a dipper, the combination of a dipper body and a supporter pivoted thereto by hinges of such size and form that said supporter cannot close the bottom of said dipper, and means located on the side of said supporter remote from the dipper for preventing the supporter swinging away from the dipper.

4. In a steam shovel dipper comprising a body closed at the front, back and sides and open at the top and bottom and a supporter hinged to the body behind the back, the front of the body extending below the sides and having means for engaging the supporter at a distance below the sides greater than the depth of the dipper body.

5. In a steam shovel dipper comprising a body closed at the front, back and sides and open at the top and bottom and a supporter hinged to the body behind the back, the front of the body extending below the sides and having means for engaging the supporter at a distance below the sides greater than the depth of the dipper body and a removable wearing plate secured to the lower edge of the front of the dipper.

6. A steam shovel dipper comprising a body closed at the front, back and sides and open at the top and bottom, and a supporter hinged to said body behind the back, the front of the body extending below the sides and having means for engaging the supporter at a distance below the sides greater than the depth of the dipper body, the back of the body having a bearing for pivoting the bail of the dipper.

E. J. MOYNIHAN.
